UNITED STATES PATENT OFFICE.

JOHN I. WARMAN, OF CHICAGO, ILLINOIS.

VELOCIPED.

SPECIFICATION forming part of Letters Patent No. 605,155, dated June 7, 1898.

Application filed October 26, 1896. Serial No. 610,033. (No model.)

To all whom it may concern:

Be it known that I, JOHN I. WARMAN, of Chicago, in the county of Cook and State of Illinois, have invented certain new and useful Improvements in Velocipedes, of which the following is a specification.

This invention relates to improvements in velocipedes, and refers more specifically to improvements in a carrier-vehicle which is 10 propelled manually and is adapted to convey one or more passengers or other commodities in addition to the persons acting to propel the vehicle, the invention being of special utility when embodied in the form of an ambulance, but being also capable of embodiment in other forms, as will hereinafter more fully appear.

Among the objects of the invention are to provide a simple, practical, light, and strong 20 vehicle which may be propelled at a relatively high rate of speed and maintained under perfect control of the drivers, and which is constructed with special reference to safety and convenience of operation.

A further object aimed at in the construction of the ambulance forming one embodiment of the invention is to produce a machine which may be handled with the utmost convenience and expedition, thereby rendering 30 the vehicle especially adapted for cases of emergency.

The invention consists in the matters hereinafter described, and more particularly pointed out in the appended claims, and the 35 same will be readily understood, reference being had to the accompanying drawings, in which—

Figure 1 is a view in side elevation of the invention embodied in the form of an ambulance. Fig. 2 is a bottom plan view of the same, showing particularly the arrangement of the running-gear. Figs. 3 and 4 are transverse vertical sectional views taken on lines 33 and 44, respectively, of Fig. 2 and looking 45 in the directions of the arrows. Fig. 5 is a side elevation of the invention embodied in the form of a carriage or road-cart. Fig. 6 is a bottom plan view of a stretcher forming a part of the equipment of the ambulance shown in Fig. 1. Fig. 7 is a side elevation of the same, showing the parts changed into position to form a reclining-chair. Fig. 8 is a

fragmentary detail showing the form of hinge employed for uniting the two parts of the main body of the stretcher. Fig. 9 is a fragmentary detail showing the holding-ratchet, by means of which the foot-support is held in proper relation to the body of the stretcher. Fig. 10 is an axial sectional detail of one of the vertical steering-wheel standards. 55

First describing the embodiment of the invention illustrated in Figs. 1 to 4, inclusive, A designates as a whole a tubular framework supported at its rear by means of two transversely opposite main supporting and driving 60 wheels and at its front by means of two other supporting and guiding or steering wheels, the said framework and several supporting-wheels corresponding generally to the running-gear of an ordinary carriage. Describ- 65 ing said parts in detail, A A' designate two upright frames arranged to extend longitudinally at opposite sides of the vehicle and each of which consists of a somewhat modified form of diamond frame, such as used in an ordinary safety-bicycle—that is to say, each frame 70 A' comprises a front steering-head standard a, a steering-spindle a', arranged to extend vertically therethrough, handle-bars a², connected with the upper end of said steering-spindle in the usual manner, a seat-post standard a³, lower front frame member a⁴ and upper frame member or backbone a⁵, connecting the seat-post standard with the steering-head standard, a saddle-post a⁶, arranged 75 to telescope at its lower end within the seat-post standard and carrying at its upper end a saddle a⁷, a crank-axle, crank-arms, and 80 pedals a⁸ a⁹ a¹⁰, respectively, mounted at the junction of the lower frame member with the 85 lower end of the seat-post standard and upper and lower rear-fork members a¹¹ a¹², respectively, connected with the upper and lower parts of the seat-post standard also in the usual manner. Within the rear forks of each 90 frame A' is mounted a main driving and supporting wheel A², which is driven from the 95 pedals by means of the usual sprockets a¹³ a¹⁴ and sprocket-chain a¹⁵. The steering-head standard is in the present construction ar- 100 ranged to extend downwardly at its lower end a considerable distance below the point of connection therewith of the lower front frame member a⁴, and a second lower front frame

member a^{16} is rigidly connected with the lower end of said standard and arranged to extend obliquely upward and rearwardly to and is connected with the frame a^4 at a point between the ends of the latter, thus rendering the lower end of the steering-head rigid with the main frame.

Next describing the supporting-frame, by means of which the bed or body of the vehicle is suspended between the upright frames hereinbefore described, B designates a transversely-arranged horizontal frame member rigidly connected at each of its ends with the inner one of the lower rear-fork members a^{12} at points between the ends of the latter, as at b .

B' designates suspension or truss members, each connected at one end with the upper part of one of the inside upper rear-fork members at the inner side of the latter, as at b' , and extending thence obliquely downward and inwardly to and connected at its lower end with the horizontal member B at a point b^2 some distance from the end of the latter.

B^2 designates a second transversely - arranged horizontal member rigidly connected at its ends with the lower ends of the steering - head standards by means of suitable union-pieces b^3 , and in order to support and strengthen the frame member B^2 between its ends braces b^4 are arranged to extend from the upper part of each steering-head standard obliquely downward to and are connected with said frame member in a manner substantially like the similar braces of the frame member B' .

With the front transverse member is connected a forwardly - extending horizontally-arranged rigid truck-frame, consisting of a lower approximately semicircular frame member B^3 , connected at its rear with said transverse frame member, so as to extend in substantially the same horizontal plane therewith, by means of curved braces or union-pieces b^5 , said braces being arranged with their concaved sides facing outwardly and arranged to extend from their points of connection with the curved member B^3 divergently outward and rearwardly, so as to unite with the transverse frame member as near the ends of the latter as practicable without interfering with the sweep of the steering-wheels C. The forward ends of the curved frame member are rigidly connected by means of a straight transverse connecting - bar B^4 . b^6 designates a union-piece or clip which is arranged to connect the rear sides of the curved frame member with the transverse frame member at the center of the latter at the point of nearest approach of said parts, and from said union-piece is arranged to rise a short rigid standard B^5 , with the upper part of which is connected a second horizontally-arranged curved frame member B^6 , arranged to extend concentrically with the lower curved frame member, but formed upon a larger radius, as indicated clearly in plan Fig. 2. The lower curved frame member

is provided at each side, at diametrically opposite points, with union-pieces or clips b^7 , with which are respectively connected short vertical tubular steering-wheel standards B^7 , the upper ends of which are rigidly connected with the forward ends of the upper curved frame member B^6 .

Within each of the tubular standards B^7 is journaled a spindle B^8 , provided at its upper end with a transverse eye or socket b^8 , (see detail Fig. 10,) within which is seated the inner end of the horizontal outwardly-projecting stub axle or spindle C', upon which is mounted the steering-wheel C.

To now describe the steering mechanism, by means of which the steering-wheels C are caused to oscillate about their vertical axes and in unison, the lower end of each of the vertical spindles B^8 is provided with a rigid horizontally - extending arm D. Upon the lower end of the standard B^5 is pivotally mounted a three-armed lever D', two of the arms d d' of which are arranged to extend at right angles to each other, while the third, d^2 , is arranged to extend rearwardly in a direction in alinement with a line dividing the angle between said arms d d' . The arms D are so arranged as to extend, when the steering-wheels are in their normal position in alinement with the body of the vehicle, obliquely forward and inwardly in a direction substantially parallel with the arm d or d' at the side of the vehicle remote therefrom, and each pair of parallel arms are connected at their outer ends by means of connecting-rods D^2 . When thus connected, it will be obvious that upon the oscillation of the three - armed lever in either direction the steering - wheels will be caused to oscillate about their vertical axes and will at the same time be maintained parallel with each other, thus causing the vehicle to diverge to the right or left, as the case may be. In order to thus oscillate the three-armed lever, the lower end of each steering-spindle a is arranged to extend below the steering-head standard and is provided with a horizontally-extending arm D^3 , arranged in the present instance to extend rearwardly and slightly inward therefrom.

D^4 designates connecting-rods, by means of which the outer ends of each of the arms D^3 are pivotally connected with the arm d^2 of the three-armed lever, thus enabling the vehicle to be steered by means of either pair of handle-bars and at the same time insuring that said handle-bars shall move in unison with each other. In order to limit the extent of oscillation of the steering-wheels about their vertical axes, stops are provided, shown in the present instance as conveniently formed integral with the arms D^3 and arranged to contact with depending tubular studs d^3 , projecting downwardly from the outer end of the transverse frame member B^2 .

It will be obvious that any suitable form of vehicle-body may be mounted upon the running-gear thus described—as, for instance, a

carriage-body such as illustrated in Fig. 5 or the ambulance-body illustrated in Figs. 1 to 4, inclusive. First describing the latter construction, referring to Figs. 3 and 4, E E' designate bolsters or supporting-bars, each suitably conformed to fit between the converging suspension-braces and to rest upon the transverse frame members B B², respectively, said bolsters being conveniently and as herein shown secured rigidly in position by means of U-shaped strap-irons e, arranged to embrace the horizontal frame members and secured to the opposite sides of the bolsters. A third bolster or supporting-bar E² is similarly secured to rest upon the cross-bar B⁴, which unites the front ends of the lower semicircular frame-bar B³, the upper surfaces of all three of the bolsters being in the present instance arranged to lie in the same horizontal plane. Upon the bolsters is mounted a flat platform or buckboard E³, provided at each side with longitudinally-extending guide-strips e', which rise some distance above the top surface of the platform. The platform is conveniently and as herein shown secured in position upon the bolsters by means of bolts or screws inserted through the upper ends of the U-shaped straps e, the upper ends of the latter being bent outwardly at right angles to the side surfaces of the bolster, so as to form angle-irons, through which and the body of the platform said bolts or screws are inserted. Upon the platform thus mounted upon the running-gear is arranged to rest and slide a removable stretcher, which may be described generally as consisting of a main body F, which has the form of an oblong substantially rectangular open-topped box composed of three sections F', F², and F³, flexibly united with each other, so as to be capable of flexing or folding upon transverse lines to permit the body of the stretcher to assume various positions, as indicated in Fig. 7.

As a convenient means for holding the stretcher in position upon the platform a plurality of rectangular links K K are pivotally attached to suitable eye-lugs k, mounted upon the side walls of the platform and adapted when turned upwardly to embrace rectangular lugs k' k', mounted to register therewith, upon the bottom frame of the stretcher, said holding-lugs being provided with transverse key-apertures, through which may be inserted pins k² to hold the links in engagement therewith.

In order to prevent the patient from exposure while being conveyed in the vehicle, a folding canopy or cover J is provided, made of canvas, leather, or other suitable material and arranged to cover and inclose the entire length of the stretcher, as indicated clearly in Fig. 1.

In the modification illustrated in Fig. 5 the running-gear is identical with that hereinbefore described, with the exception that the bolsters and platform are omitted and in lieu thereof a three-seated carriage-body L is

mounted upon the vehicle. The rear end of said body is suitably secured directly upon the rear transverse supporting-frame member, while the front end thereof is provided with a platform suitably conformed and arranged to rest directly upon the curved lower horizontal frame member B³ and connecting-bar B⁴. Inasmuch as the details of this carriage-body may be varied as desired or to suit the particular want and form no part of the present invention, they need not be further described herein.

I claim—

1. In a velocipede, the combination of two parallel, laterally opposite, upright frames and rear driving-wheels mounted therein a saddle above each of said wheels, pedal mechanism for driving each wheel independently of the other, horizontal transversely-arranged supporting-bars extending between and rigidly connecting said upright frames at points between the driving-wheels and at their front ends respectively, a steering-truck connected with the central part of the foremost one of said transverse members, steering-wheels connected with said steering-truck at each side thereof, steering-handles in front of each saddle and interconnecting means between said handles and the steering-wheels whereby the latter may be turned by either rider, the arrangement of the transverse supporting-bars, and the steering-truck being such that an open space is provided between the pairs of wheels adapted to receive a stretcher arranged horizontally at full length with the head and foot ends of the same projecting beyond the axes of the front and rear pairs of wheels respectively.

2. In a velocipede, the combination of two parallel, laterally opposite, upright frames and rear driving-wheels mounted therein a saddle above each of said wheels, pedal mechanism for driving each wheel independently of the other, horizontal transversely-arranged supporting-bars extending between and rigidly connecting said upright frames at points between the driving-wheels and at their front ends respectively, a steering-truck connected with the central part of the foremost one of said transverse members, vertically-arranged steering-wheel spindles revolubly mounted one at each side of said steering-truck, steering-wheels mounted upon said spindles so as to oscillate about the latter, steering-handles in front of each saddle and interconnecting means between said handle and the steering-wheel whereby the latter may be turned by either rider, the arrangement of the transverse supporting-bars and steering-truck being such that an open space is provided between the pairs of wheels adapted to receive a stretcher arranged horizontally to rest at full length upon said members with the head and foot ends of the same projecting beyond the axes of the front and rear ends of wheels respectively.

3. A carrier-velocipede comprising two lat-

erally-supported transversely opposite upright driver-supporting frames, each embracing wheel-forks, steering-spindle, handle-bars and pedals, a driving-wheel mounted in the forks of each upright supporting-frame and driving connections between the pedals thereof and said driving-wheel, a horizontal supporting-frame suspended between said upright frames and supported at its front by means of a pair of transversely opposite steering-wheels arranged to oscillate upon separate vertically-arranged steering-spindles located at each side of and in rear of the front end of the horizontal frame and interconnections between the individual steering mechanism of the upright frame and said steering-spindles whereby the steering-wheels are caused to move in unison.

4. The combination of the upright frames

A A', provided with the driving-wheels and driving mechanism, the transverse rear and front frame members B B², respectively, the truck-frame member B³ rigidly connected with the transverse frame member B²; the vertical oscillatory spindles B⁸ connected with the opposite sides of said truck-frame member and the interconnected steering mechanism, whereby the vehicle may be steered by either driver, substantially as described.

In testimony that I claim the foregoing as my invention I affix my signature, in the presence of two witnesses, this 15th day of October, A. D. 1896.

JOHN I. WARMAN.
